UNITED STATES PATENT OFFICE.

HERBERT O. McGREGOR, OF MORGANTOWN, WEST VIRGINIA.

COMBINED TIE AND BOLTLESS RAIL-JOINT.

Specification of Letters Patent.

Application filed August 21, 1920. Patented July 12, 1921.

Serial No. 404,997.

1,384,700.

To all whom it may concern:

Be it known that I, HERBERT O. McGREGOR, a citizen of the United States, residing at Morgantown, in the county of Monongalia and State of West Virginia, have invented new and useful Improvements in Combined Tie and Boltless Rail-Joints, of which the following is a specification.

This invention relates to a combined tie and boltless rail joint, the general object of the invention being to provide means for holding the rails in place without the use of spikes and for joining the ends of the rails together without the use of bolts.

15 Another object of the invention is to provide a plate, adapted to rest upon a suitable base, or a base member itself, provided with openings for slidably receiving rail engaging members, with means for locking said

20 members in engaging position.

Another object of the invention is to provide the fish plates at the rail joints with notches and to make some of the locking members with head parts for engaging said

25 notches for holding the plates against the rails.

A further object of the invention is to provide locking pins and receiving openings for the pins in the rails and the fish plates for

30 securing said plates to the rails.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote the several views, and in which:

Figure 1 is a plan view showing a portion of a railway constructed in accordance with my invention.

Fig. 2 is a section on line 2-2 of Fig. 1.

Fig. 3 is a section on line 3-3 of Fig. 1.

Fig. 4 is a section on line 4-4 of Fig. 1.

Fig. 5 is a face view of one of the fish

50 plates.

Fig. 6 is a sectional view on line 6-6 of

Fig. 1.

As shown in these views I locate the rail holding devices on a plate 1 which may be secured to a tie or any other suitable form of

55

base or I may make the plate 1 thick enough to take the place of the tie. The plate 1 is provided with an elongated groove 2, adjacent each end thereof which is provided with a wide part 2' at each end, having straight walls, the rest of the groove being narrow and provided with undercut walls as shown at 2''. While the drawing shows the plate as being grooved it will be understood that the plate may be slotted, the bottom of the slot being closed by the tie or other base. Loops 3 are provided at each side of the wide parts of the groove, these loops being preferably formed by punching up the metal of the plate, as shown in Fig. 3. The rails A are adapted to pass over the central parts of the plate, as shown in Fig. 1, and in order to hold the rails in position on the plates I provide locking members 4. These members each consists of a dove-tailed base 5 and an upwardly extending head 6 which is connected with the intermediate the ends thereof. Each head is formed with a recess 7 to receive the flange of the rail, the rail overlapping as shown in Figs. 1 and 6. There is on each side of the rail with their of these locking members in each groove on each side of the rail with their dove-tailed bases engaging the rail with their flanges and thus holding the rail in position. The groove and in order to hold the members in locking position I provide fillers 8 which occupy the wide parts 2' in the narrow part of the groove. The fillers plates are held in position by 9 which are passed through the base which have their ends bent over them from sliding off the base plates pass over the filler plates seen. In order to remove the members it is simply necessary to do 9 through the loops, lift out the wide parts 2' of the locking members and then slide the locking members from the plate. The fi

gaging the outer ends of the locking members will hold the members with their heads in fi with the rails and thus in fi

ment of the rails on the bas

pler to facilitate the plac

plates in the wide parts of their removal therefrom I

edge of each plate as sho

and I also provide each plate with a central opening 8" for receiving a pick or bar for raising the plates from the grooves.

The rail joints are formed by the fish plates 10 which are connected with the rails by the pins 11 engaging holes formed in the said plates and in the webs of the rails. These fish plates are provided with notches 12 upon their outer faces for receiving the heads of these members which engage the fish plates are made considerably larger than the heads of the other members and they are provided with vertical faces for engaging said notches. In other respects these locking members are similar to those for holding the rails to the base plates.

As will be seen from Fig. 2, the inner ends of the dove-tailed bases of the locking members extend under the rails and the rails are engaged by said locking members at the edges and upper and lower faces of their bases.

By my invention the use of spikes for holding the rails to the ties and the use of bolts for connecting the fish plates to the rails are eliminated. The rails are securely clamped in place and movement of the parts is prevented by the walls of the grooves, the parts being held in the grooves the action of gravity and also by the

9. All the parts of my invention can be over and over again until worn as will not be damaged by being removed and placed in removing the old rails and putting new ones as is the case where and bolts are used.

10. The advantages and novel features of the invention will be readily apparent. It is to be understood that I may make changes in the construction and in the on and arrangement of the several

parts, provided that such changes fall within the scope of the appended claims.

What I claim is:—

45

1. In combination with the rails of a track, base members each having a pair of grooves therein, each groove consisting of a narrow central part provided with undercut walls and wide end parts, a pair of locking members in each groove, each member including a dove-tailed base and a head extending upwardly from the base intermediate its ends and having a recess for receiving the flange of the base of the rail, filler plates fitting in the wide part of the grooves for holding the locking members in locking position, loops at the sides of the wide parts of the grooves and locking bars passing through said loops and over the filler plates.

2. In combination with the rails of a track, base members for supporting the rails, each member having a pair of grooves therein, each comprising a dove-tailed base and an upwardly extending head having a recess therein for receiving the flange of the base of the rail, locking means for holding the locking members in locking position, fish plates for the ends of the rails, said plates having notches therein and some of the locking members having enlarged heads for engaging said notches.

3. A rail joint comprising a pair of fish plates having notches in their outer faces and holes in their inner faces, pins engaging said holes and holes in the webs of the rails, grooved plates under the rails, locking members consisting of base portions and upwardly extending heads, said heads engaging the notches and the base portions for locking the members in locking position.

In testimony whereof I affix my signature.

HERBERT O. McGREGOR.
